UNITED STATES PATENT OFFICE.

JOHN DOUGLAS MACKENZIE AND RICHARD W. SENGER, OF GARFIELD, UTAH, ASSIGNEES TO AMERICAN SMELTING AND REFINING COMPANY, OF NEW YORK, N. Y., A CORPORATION OF NEW JERSEY.

FURNACE-ROOF CONSTRUCTION.

Application filed April 2, 1927. Serial No. 180,412.

This invention relates to furnace roofs, and, more particularly, to a roof construction for reverberatory furnaces having means for absorbing heat from the refractory lining thereof.

The invention relates more specifically to a roof construction comprising a plurality of water cooled blocks which may be independently positioned and supported, the blocks being provided with downwardly extending metallic web-like members or fins between which the refractory lining is secured.

Various other features and advantages of the invention will be apparent from the following particular description and from an inspection of the accompanying drawings.

Due to the excessive heat in the interior of a reverberatory furnace and particularly over the hearths of such furnaces, the refractory lining is subject to considerable wear which results in comparatively rapid disintegration of the surface portion thereof. When the disintegration has proceeded to such an extent that the thickness of the lining is reduced below the required point, the roof must either be renewed or repaired with the consequent withdrawal of the furnace from active service.

In order to minimize as far as possible the erosion of the lining and to reduce the frequency of the periods during which the furnace must be withdrawn from use for the purpose of making repairs, it is desirable to provide a means for absorbing heat from the lining material at a sufficient rate to prevent the surface from becoming excessively hot.

This is accomplished in accordance with the present invention by providing a water cooled casting adapted to be suitably positioned to cover the entire roof of the furnace and having downwardly extending web-like members formed integral therewith. The weblike members are adapted to extend between the various refractory brick forming the lining of the roof and to rapidly conduct heat away from the adjacent portions thereof to the metallic casting itself wherein the heat is absorbed by a circulating cooling medium. The above described castings are formed in comparatively small blocks which may be selfsupporting in the form of an arch or, if desired, may be mechanically supported by an external strengthening member.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a plan view of a water cooled block constructed in accordance with this invention;

Fig. 2 is a broken bottom view thereof showing the location of the cooling fins;

Fig. 3 is a section taken on the line 3—3 of Fig. 1 and

Fig. 4 is a broken sectional view of a reverberatory furnace having a roof composed of the water cooled blocks.

Like reference characters denote like parts in the several figures of the drawings.

In the following description and in the claims parts will be identified by specific names for convenience, but they are intended to be as generic in their application to similar parts as the art will permit.

Referring to the figures more in detail the invention is shown as comprising a metallic casting 10, of copper or other material having a high co-efficient of heat transmission, in which are embedded coiled pipes having upstanding end portions 12 to facilitate external connections thereto. Supporting rings 13 may be embedded in casting 10 and rigidly secured thereto in any suitable manner, such as by being cast therein.

A plurality of radiating fins 14 of the same metal as casting 10 are formed integral therewith and are suitably spaced to receive the desired refractory material such as tile or brick 15. Casting 10 may be formed slightly wedge-shaped to provide the usual arch construction although the bricks or tiles employed are preferably rectangular in form so that when a plurality of blocks are positioned to form an arch the increased pressure on the lower portion thereof will serve to hold the various brick or tile in firm engagement with fins 14 and prevent the former from being displaced downwardly after the completed roof has been installed.

As shown in Fig. 4 a plurality of sections 10 may be positioned side by side to form

the arched roof of a reverberating furnace and may rest upon side walls 20 which may be of the usual construction such as brick as shown. Metallic side members 21 may be employed for strengthening side walls and may be joined by rod 22 for the purpose of preventing the side walls from spreading.

- Blocks 10 may be mechanically suspended from rod 22 if desired by means of links 10 23 attached to said rod and cooperating with rings 13. The blocks supported in this manner may be independently removed without destroying the whole arch each time it is desired to remove a single block. The various cooling pipes 11 may be joined in any suitable manner as by members connecting the upstanding ends 12 to provide for continuous circulation of water or other cooling medium through the entire roof.
- 20 The heat which is absorbed by the refractory tile 15 will be applied directly to the fins 14 and conducted by said fins to the main water cooled portion of the roof 10. Fins 14, being of a material which is capable of conducting heat more readily than the refractory tile commonly employed in furnace construction, operate to absorb the heat from the refractory tiles and to rapidly conduct the same to the main portion of the casting wherein it is taken up by the circulating fluid.

Metallic fins 14 cool the surface of the refractory bricks much more readily than would be possible were the heat from the surface of the brick forced to pass through the entire depth of the brick and to be conducted therethrough to the cooling medium. Not only is the surface of the brick kept in comparatively cool condition by reason of the circulating fluid and by reason of its direct contact with the water cooled blocks, but the lower surface is cooled with greater facility since a large portion of the heat therefrom is absorbed directly by the radiating fins without the necessity of passing through the entire layer of refractory material.

Should it become necessary to remove a block from the furnace roof for purpose of repair or replacement, connecting members 13' may be removed from pipes 12 and the block lifted bodily from the arch by applying the lifting force directly to rings 13. Supporting members 23 will then prevent the entire roof from collapsing and serve to retain the remainder of the blocks in their proper position.

In the drawings accompanying and forming part of this specification, a practical commercial embodiment of the invention is disclosed, but as such illustration is pri-

marily for purposes of disclosure, it will be understood that the structure may be modified in various respects without departure from the broad spirit and scope of the invention as hereinafter defined and claimed. 65

What is claimed is:

1. A block adapted to form a portion of a furnace roof comprising a metallic casting having radiating fins extending downwardly therefrom to substantially the inner surface of said roof, said fins of material having high heat conductivity being suitably spaced to permit the insertion of refractory tile therebetween and to conduct heat from the inner surface of said tile to said casting. 70

2. A block adapted to form a portion of a furnace roof comprising a metallic casting having pipes embedded therein for the circulation of cooling fluid, fins extending downwardly from said casting, said fins being suitably spaced to permit the insertion of refractory tile therebetween and to conduct heat from the inner surface of said tile to said casting. 80

3. A block for use in reverberatory furnaces comprising an exterior casting having pipes embedded therein for the circulation of a cooling fluid and internally extending metallic web members, refractory members between said web members adapted to form the lining of said furnace, said refractory material being held in position by the friction of the sides of said web members. 90

4. A furnace roof comprising a plurality of blocks, each of said blocks comprising a casting having internally extending heat absorbing flanges and refractory material between said flanges adapted to form the lining of said furnace and held in position by the friction thereof said flanges being adapted to remove heat from the surface of said material and to conduct said heat to the aforementioned casting. 100

5. A furnace roof comprising a plurality of blocks, each of said blocks comprising a water cooled casting having internally extending heat absorbing flanges integrally formed therewith and refractory material between said flanges adapted to form the lining of said furnace and held in position by the friction thereof, said flanges being adapted to remove heat from the surface of said material and to conduct said heat to the aforementioned water cooled blocks. 110
